UNITED STATES PATENT OFFICE.

EDWARD THERAUL, OF SAN FRANCISCO, CALIFORNIA.

WINDOW-CHAIR.

1,149,165.

Specification of Letters Patent.

Patented Aug. 3, 1915.

Application filed March 10, 1915. Serial No. 13,361.

To all whom it may concern:

Be it known that I, EDWARD THERAUL, a citizen of the United States, residing in the city and county of San Francisco and State of California, have invented new and useful Improvements in Window-Chairs, of which the following is a specification.

This invention relates to window chairs, and particularly to that class of portable seats which is adapted to be used on the outside of windows while cleaning same.

One of the objects of the present invention is to provide a window bracket or chair which is simple, substantial and inexpensive in construction, easy to manipulate, capable of being easily and quickly placed in position, and removed therefrom, and which is so constructed and arranged that it may be folded into compact shape or form for the purpose of transportation or storage.

Another object of the invention is to provide clamping members for securing the seat on the window sill, when in use, and to provide adjustments whereby said clamping or gripping members may be adjusted to fit various sized and shaped sills.

Further objects will hereinafter appear.

The invention consists of the parts and the construction and combination of parts as hereinafter more fully described and claimed, having reference to the accompanying drawings, in which—Figure 1 is a perspective view of the chair. Fig. 2 is a side elevation of the chair in folded position, showing it placed in position on a window sill and ready to be opened out. Fig. 3 is a central, longitudinal section through the chair, showing the adjustments provided in connection with the main clamping or gripping member. Fig. 4 is a bottom view of Fig. 3. Fig. 5 is an enlarged detail view of the adjusting means provided in connection with the exterior gripping members.

More particularly described, A indicates the seat portion of the chair and 2 the back. The back is in this instance pivotally mounted to the seat, as indicated at 3, and is adapted to be folded up for storage or shipment, as indicated in Fig. 2. Pivotally mounted on each side of the back, on an extension bracket 4, is a link 5, and pivotally mounted on each side of the seat, as at 6, is a link arm 7, to which the lower ends of the links 5 are pivotally connected, as at 8. The upper ends of the links 5 are connected by a cross arm 9 and this arm is grasped and swung forwardly in the direction of arrow α

when it is desired to fold the back with relation to the seat. The links 5 and 7, together with the operating cross arm 9, are provided for the purpose of locking the back when in the open position, thus preventing the back from accidentally swinging forward and releasing the gripping members, as herein-after to be described.

Suitably secured under the seat A, near each forward corner, is a bracket 10, and secured under each bracket is a supporting member 11 which is preferably faced with a rubber pad 12, or the like, to prevent the wood of the sill from being marred. Hingedly mounted on the rear end of each supporting member 11, as at 13, is a clamping member 14, the face of which is also padded with rubber 15 or like material. Extending up from each clamping member 14 is an arm 16, and connecting the upper end of each arm with the back of the chair is a link 17. The opening or folding of the back section of the chair is in this manner transmitted through the links 17 to swing the gripping members 14 about their pivots 13 to move same into a horizontal or vertical position; the vertical position being assumed when the back is opened out and the horizontal position, such as indicated in Fig. 2, being assumed when the back is folded with relation to the seat. The movements, as before described, are transmitted through the links 17.

Adjustably mounted underneath the seat proper is a forwardly extending arm 18. The inner end of said arm is turned down or shaped substantially as shown, and secured on the lower end of said arm is a gripping bar 19 of suitable length. This may also be faced with rubber or like material.

In operation, when it is desired to wash a window, it is only necessary to place the chair in position, as indicated in Fig. 2. Cross arm 9 is then grasped and swung in the direction of arrow β . This will cause links 7 to swing outwardly about their pivots 6 and this movement will in turn be transmitted through the links 5, which are connected with the links and the back of the chair, to cause the back to be raised and swung out to the position indicated in Fig. 1. The links 5 and 7 when completely opened out will in this instance form a lock and prevent the back from accidentally swinging forward. The opening movement of the links 5 and 7 and back 4 is at the same time transmitted through the links 17 and

arms 16 to swing the gripping members 14 downwardly and inwardly in the direction of arrow *c*, causing the gripping members to securely grip or engage the outer edge of the window sill, such as indicated at 20. The main gripping bar 19 and arm 18 will in this instance extend into the room and grip the lower and inner side of the window casing. The chair is thus securely locked and clamped in position and ready for use. For the purpose of making the clamping or gripping members on the chair adjustable to different sized sills or window casings the following adjustments have been provided: Referring to Figs. 3 and 4, it will be seen that an adjustable bar 21 has been provided and is slidably connected to seat A. The inner end of this bar is turned down, as indicated at 22, and a screw bolt 23 extends through said end. The bolt, when turned by means of the nut 24, will cause bar 21 to move in one direction or the other.

Pivotedly mounted in the outer end of bar 21, as at 25, is a pair of links 26, and pivotedly mounted, as at 27, on the inner end of arm 18 is a second screw bolt 28. This bolt extends through a bar 29 which in turn is pivotedly mounted between the links 26. The pivotal mounting of bolt 28 permits this to be swung about pivot 27, as indicated by dotted lines at 30, causing arm 18 to be moved out or in according to the position of the swinging bolt 28. The arm 18 will be moved to its innermost position when bolt 28 is in the position shown in Fig. 3 and will be in its outermost position when swung into the opposite position. This adjustment, together with the adjustment secured by the screw bolt 23, permits a wide range 40 of movement and sufficient adjustment to fit in the window sill.

The supporting members 11 are also adjustable, such as indicated at 34 in Fig. 5. This permits a vertical adjustment to secure any desired slope of the seat. The main gripping bar 19 is also adjustably clamped to arm 18, as indicated, thus permitting same to be adjusted to engage with desirable offsets or ridges on the inner side 50 of the window casing.

A chair or seat constructed as here shown is simple in construction, is quickly and easily removed from the window casing when not in use, and may be folded in compact form for storage.

The materials and finish of the several parts of the device are such as the experience and judgment of the manufacturer may dictate.

I wish it understood that various changes in form, proportions and minor details of construction may be resorted to within the scope of the appended claims, and that I do

not wish to limit myself to the specific design and construction here shown.

65

Having thus described my invention, what I claim and desire to secure by Letters Patent is—

1. In combination with a base, a horizontal gripping member secured to the base, a vertical gripping member pivoted to the horizontal gripping member, an arm secured to the vertical gripping member and extending above the pivotal point thereof, a back pivoted to the seat, and a link pivoted at one end to the back above the pivotal point of the latter and having its other end extending below the pivotal point of the back and pivoted to the upper end of the arm.

2. In combination with a seat and a back pivoted thereto, rearwardly extending brackets on the back below the top of the latter, links pivoted at their ends to the respective brackets, link arms pivoted at their lower ends to the seat and pivoted to the lower ends of the respective links, and a cross arm connecting the upper ends of the link arms.

3. In combination with a seat, and a back pivoted thereto, a gripping member mounted forwardly of the back and independent of the back and means pivotally connected to the back and member for operating the latter from the back.

4. In combination with a seat and a back pivoted thereto, links pivoted to the seat and extending at their upper ends beyond the back when the latter is in normal position, links pivoted to the back and to the first named links, and a cross-member connecting the upper ends of the first named links to operate same in unison.

5. In combination with a seat and a back pivoted thereto, devices on each side of the back connected thereto and to the seat for locking the back against accidental pivotal movement, and means connecting said devices for operating same in unison and disposed in non-interfering position with respect to the seat when the back is in open position.

6. In a window bracket, a base, a member secured to the base and therebeneath, a clamping arm beneath the base, a screw bolt pivoted to said arm, a pair of connected links pivoted to said member, and a bar pivotally connected to the links and through which said bolt threadedly engages.

In testimony whereof I have hereunto set my hand in the presence of two subscribing witnesses.

EDWARD THERAUL.
